UNITED STATES PATENT OFFICE.

LEOPOLD ALMQUIST, OF NEW YORK, N. Y., AND VICTOR WILLOUGHBY, OF RIDGEWOOD, NEW JERSEY, ASSIGNEES TO AMERICAN CAR AND FOUNDRY COMPANY, OF NEW YORK, N. Y., A CORPORATION OF NEW JERSEY.

MINE CAR.

Application filed July 17, 1926. Serial No. 123,189.

In the drawings:

Fig. 1 is a view partly in longitudinal section and partly in side elevation with a wheel and part of an axle broken away, of a mine car constructed in accordance with this invention;

Fig. 2 is a partial longitudinal section taken adjacent the sill in Fig. 4 and showing the drop doors in closed position;

Fig. 3 is a partial horizontal section taken on the line 3—3 of Fig. 2;

Fig. 4 is a partial vertical transverse section taken on the line 4—4 of Fig. 2;

Fig. 5 is a plan view of one corner of the free edge of one of the doors forming the floor of the car;

Fig. 6 is a partial transverse section taken on the line 6—6 of Fig. 2 and shows another view of the corner shown in Fig. 5;

Fig. 7 is a view similar to Fig. 2 showing in solid lines one door in dropped position and the latch operated by that door and showing in dotted lines the closed position of the adjacent door and the full open position of the latch operating door;

Fig. 7^a is a fragmentary section similar to Fig. 7 showing the relative positions of a door latch and its operating cam as the cam returns the latch to door holding position.

Fig. 8 is a view similar to Fig. 2 showing a modified construction;

Figs. 9 and 10 are sections taken on lines 9—9 and 10—10, respectively, of Fig. 2, and

Figs. 11 and 12 are sections similar to Figs. 9 and 10 of modifications of the structures shown in Figs. 9 and 10, respectively.

This invention relates to mine cars of the drop bottom type wherein the bottom consists of a plurality of doors hinged at one end and operating the latch of an adjacent door, and it is an object of this invention to provide an improved latching means which will be operated by the movements of one door to control the operation of an adjacent door. It is also an object of this invention to provide an improved latch engaging means on the door which will re-inforce the corner of the door.

In the drawings, the invention is shown applied to a mine car comprising side sills 1 and end sills 2 both being of channel shape and having their flanges projecting outwardly. The side sills and end sills are secured together at their ends by angle mem-

bers 4 and the end sills support bumpers 5 and drawbars 6 of suitable construction, the bumpers and drawbars being provided with openings for the usual coupling pins 8. To the upper flanges 10 of the side sills 1 are secured the inner edges of the side sheets 12, the side sheets 12 being joined at their end by the end sheets 14 secured thereto by the inwardly bent flanges 15 of the end sheets. The end sheets 14 are spaced inwardly from the end sills 2 and extend downwardly between the side sills 1. The car is supported on wheels 16 mounted on axles 18 which extend through openings in the side sills 1 and are journaled in boxes 19 secured to the side sills.

The floor of the car consists of a plurality of doors 20, 22 and 24 formed of sheet metal and having their side edges bent upwardly to form stiffening flanges 26 which extend substantially from end to end of the doors and project above the lower edges of the side sills to prevent loss of the contents of the car between the side sills and the doors. The door 20 is provided with hinge straps 28 which engage a shaft 30 mounted in bearing brackets 32 secured to the lower flanges 34 of the side sills. In the construction shown in Figs. 1 to 7 the doors 22 and 24 are provided with hinge straps 35 which engage short shafts 36 having their outer ends journaled in bearing brackets 38 secured to the flanges 34 of the side sills and their inner ends journaled in bearing brackets 40. The bearing brackets 40 are provided with outwardly projecting flanges 42 by which they are secured to outwardly projecting flanges 44 of channel-shape braces or hood members 46 which extend between the side sills 1 and are provided at their ends with laterally extending flanges 48 by which the members 46 are secured to the webs 50 and upper flanges 10 of the side sills 1.

The hinge straps 35 are provided with cam-shaped portions 51 formed integrally therewith which engage pivotally mounted latch members 52. The latch members 52 are journaled on pins 54 which are mounted in the webs 50 of the side sills and in the hoods 46, the hoods being enlarged at their ends to provide openings to receive the latch members 52. The pins 54 are retained in position by heads 56 and cotter pins 58. The doors 20 and 22 are cut away at the corners

of their free edges to provide openings for the latch members 52 and the door sheets are reenforced at these points by members 62 provided with curved downwardly projecting lugs 64 which are engaged by the projecting portions 60 of the latch members 52 to retain the doors in the closed position. The door 24 is provided with an outwardly projecting lug 66 which is engaged by a latch member 68 of suitable design, such as is shown in the patent to Nichols 1,534,135, April 21, 1925.

In operation, assuming the doors to be closed, as shown in Fig. 1, operating the latch 68 by any desired means, such as shown in patent to Nichols mentioned above, will release the lug 66 permitting the door 24 to drop, and operate the cam member 51 on the door 24. Operation of the cam 51 will cause it to be moved from the position shown in Fig. 2 in which the surface 70 of the cam is in engagement with the surface 71 of the latch member and holds the latch member in engagement with the lug 64 on the door 24 bringing the surface 72 of the cam 51 first into engagement with the surface 73 of the latch member 52 and then, as the cam is further operated, into engagement with the surface 74 of the latch 52 operating the latch 52 to withdraw the projection 60 of the latch from beneath the lug 64, and permitting the door 22 to drop. Movement of the cam 51 will be continued as the door 24 drops until the surface 70 of the cam is brought beneath the surface 73 of the latch in which position the door will be in its normal fully open position, as shown in solid lines in Fig. 7, and the latch will be held free of the door 22. To prevent the latch 52 dropping in back of the cam 51 should the door 24 swing beyond the position shown in solid lines in Fig. 7, the outer surface 70 of the cam 51 is continued by means of a wing portion 75 at one end of the cam 51 which will engage with the surface 73 and retain the latch 52 in its raised position until the surface 76 on the hinge member 35 engages with the bottom surface 77 of the projecting portion 60 of the latch member 52 and prevents further movement of the door 24. Releasing the latch 52 from the door 22 permits the door 22 to drop and operate the latch 52 which retains the door 20 in the closed position in the same manner.

The doors are returned to closed position in the reverse order by any suitable means as by that shown in the patent to Nichols previously mentioned, the door 20 being raised to its fully closed position before the door 22 is operated to return the cam 51 to the position shown in Fig. 2 in which the surface 70 of the cam 51 is in engagement with the surface 71 of the latch 52 and the latch is held in the door retaining position. Should the latch fail to fall to door retaining posi-

tion upon movement of the cam 51 the surface 78 of the cam 51 will engage first with the surface 71 and then with the surface 79 of the latch 52 forcing the latch 52 to the door retaining position as the door 22 is returned to its fully closed position in which position the surface 70 of the cam 51 is in engagement with the surface 71 of the latch 52 and holds the latch in the door retaining position. It will be noted as shown in Figs. 7, 9, and 10 that the projecting portion 60 of the latch 52 is cut away to permit passage of the wing portion 75 of the cam 51 as the cam 51 is operated. The door 24 will be closed in the same manner as the door 22 bringing the latch 52 into engagement with the lug 64 on the door 22 as the door 24 is returned to its fully closed position. Also in its fully closed position the door 24 brings the lug 66 into engagement with the latch 68 thereby locking all of the doors in the fully closed position.

In the modification shown in Fig. 8 the hinge straps 35 for the doors 22 and 24 are rotatably mounted upon the axles 18' and 20' are provided with cams 51' which operate the latches 52' mounted on pins 54' as in Figs. 1 to 7. Each latch 52' is provided with an outwardly projecting portion 60' which is in engagement with the lug 64' on the member 62' carried by the adjacent door. As in the other construction, the dropping of the door will cause the surface 72' of the cam 51' to engage with the surfaces 73' and 74' of the latch 52', the cam 51' moving the latch from the door retaining position to a position in which the surface 70' of the cam is in engagement with the surface 73' of the latch and serves to hold the latch in released position. In this construction the surface 70' of the cam will remain in engagement with the surface 73' of the latch should the door swing past its normal fully opened position and will retain the latch in its released position until the hinge strap 35' engages with the surface 77' of the latch and stops further movement of the door, thus preventing the latch from dropping in back of the cam 51'. In the closing operation of the doors, the surface 78' of the cam will be brought into engagement with the surfaces 71' and 79' of the latch should the latch fail to return to its door retaining position by gravity, thus forcing the latch to its door retaining position until in the fully closed position of the doors the surface 70' of the cam 51' will be in engagement with the surface 71' of the latch 52' and hold the latch in the door retaining position.

In the modifications shown in Figs. 11 and 12, the cam 51'' is provided with winged portions 75'' at each side instead of on one side as shown in Fig. 9, serving to more effectively hold the cam and the latch in proper relation. In order to cooperate with the cam 130

of Fig. 11 the latch 52" of Fig. 12 is cut away on both sides to receive the wing portions 75" instead of being cut away on one side as in Fig. 10.

5. What is claimed is:

1. In a mine car, a plurality of pivotally mounted doors, a latch for one of said doors, and a cam on the other of said doors to operate said latch to release said first door, said cam serving to hold said latch in door retaining position.

10. In a mine car, a plurality of pivotally mounted doors, a latch for one of said doors and a cam on the other of said doors to operate said latch to release said first door, said latch limiting the opening movement of its operating door.

15. In a mine car, a pivotally mounted door, a pivotally mounted latch for said door, a second pivotally mounted door having a cam for operating said latch to release said first door, said cam holding said latch in door-retaining position and said latch limiting the opening movement of its operating

20. door.

25. In a mine car, a pivotally mounted door, a pivotally mounted latch for said door, a second door, a hinge strap for pivotally supporting said door, and a cam on said hinge strap operatively engaging said latch and adapted to hold said latch in door releasing position.

30. 35. In a mine car, a pivotally mounted door, a pivotally mounted latch for said door, a second pivotally mounted door having a cam for operating said latch, said cam engaging said latch to retain it in door retaining and door releasing positions.

40. 45. 5. In a mine car, a pivotally mounted door, a second pivotally mounted door having a cam operatively engaging said latch, said cam retaining said latch in door retaining and door releasing positions and said latch limiting the opening movement of its operating door.

60. 65. 7. In a mine car, a pivotally mounted door, a pivotally mounted latch for said door, and a second pivotally mounted door having a cam operatively engaging said latch, said cam holding said latch in door releasing position and said latch limiting the opening movement of its operating door.

8. In a mine car, a door, a latch and means carried by said door to engage said latch, said door being cut away to receive said means and said means reinforcing said door.

9. In a mine car, a door, a latch and means to engage said latch carried by said door, said door being cut away at a corner to receive said means and said means reinforcing said corner.

10. In a mine car, a door cut away at a corner, reinforcing means for said corner having a projection thereon and a latch to engage said projection.

11. In a mine car, a door cut away at a corner, a latch for said door and reinforcing means for said corner having means to engage said latch.

12. In a mine car, a door latch, a door cut away to receive said latch and means carried by the door to engage said latch, said means reinforcing said door.

70. 75. In witness whereof we have hereunto set our hands.

LEOPOLD ALMQUIST.
VICTOR WILLOUGHBY.
